HECTOGRAPH CARBON AND COPY SHEET
ASSEMBLY

Richard V. Bowman, Philadelphia, Pa., assignor
to Kee-Lox Manufacturing Company, Rochester, N. Y., a corporation of New York

Application December 14, 1938, Serial No. 245,693

5 Claims. (Cl. 41—31.6)

This invention relates to a hectograph carbon and copy sheet assembly, with particular reference to a combination of separate carbon and copy sheets so related that the latter can be prepared for use on either the spirit type or rotary style duplicating machines where the master copy is attached to a cylinder, or on the gelatin pad reproducer, and it has for its object to afford a practical and economical construction in which the carbon and copy sheets are held together against accidental relative displacement by means that permits their quick and easy separation when desired, the relation of the sheets being such that the hectograph coated surface on the carbon sheet is covered and protected by the copy or record sheet.

One of the chief difficulties in the use of hectograph coated carbon sheets is that the coating material easily stains the fingers of the operator, it being difficult to remove such stains, and it is a purpose of the invention to provide a hectograph carbon coated sheet and a copy or record sheet which entirely covers and protects the hectograph coating so as to prevent the operator's fingers from touching it when the sheets are in their normal assembled relation, and which also enables the operator to remove the copy or master sheet from the carbon sheet quickly and readily without at any time touching the carbon coating, and furthermore permitting repeated use of such a carbon sheet by enabling the operator to insert a fresh copy or record sheet, repetition of this process being possible until the hectograph carbon coating is entirely used.

Another purpose of the invention is to provide a construction in which the hectograph carbon coating can be on one weight or grade of paper best suited for the purpose, while the copy or record sheet can be of another or heavier grade of paper, the two sheets being entirely separate and independent from each other, but held in interlocked or assembled relation by movable interengaging retaining means.

A further object of the invention is to provide a record or copy sheet positioned over the carbon coated surface of a hectograph sheet, one of said sheets being provided with instrumentalities extending along opposite edges, overlying the outer surface of the other sheet and thereby holding the sheets in operative copying relationship, affording means for enabling the operator to hold the carbon sheet with one hand while removing the copy or record sheet with the other hand without contacting the hectograph coating, the copy or record sheet being provided with means extending be-

yond the carbon sheet for grasping it and separating the sheets.

The invention also has for an additional object the provision of means that enables positioning the sheets in a typewriter at different positions in relation to the line of writing when making successive copies, so that the carbon coating is uniformly used over the entire sheet by staggering the lines of writing through the carbon coating in making successive copies.

To these and other ends, the invention consists in the construction and arrangement of parts that will appear clearly from the following description when read in conjunction with the accompanying drawing, the novel features being pointed out in the claims following the specification.

In the drawing:

Fig. 1 is a plan view of a preferred embodiment of the invention looking toward the copy or record sheet, the latter being partially broken away;

Fig. 2 is a similar view, with the copy or record sheet removed, and showing the retaining flanges or tabs of the carbon sheet unfolded;

Fig. 3 is a view in elevation of the copy or record sheet removed from the carbon sheet;

Fig. 4 is a detail view partially broken away of the copy sheet with typewriting thereon, the record from the carbon being in reverse on the opposite side of the sheet, for use with a rotary style duplicating machine;

Fig. 5 is a similar view of the opposite side of the copy sheet showing the record as used on the duplicating machine;

Fig. 6 is a sectional view on the line 6—6 of Fig. 1, and

Fig. 7 is an enlarged view in elevation of the folded-over flange of the carbon sheet, illustrating the means for positioning the sheet in a typewriter when making a record on the copy sheet.

The invention may be carried out in several different ways, the embodiment of this application being exemplary of one practical form, and referring more particularly to the drawing in which like reference numerals refer to the same parts throughout the several views, 1 designates a copy or record sheet provided at one end with an extension or finger portion 2, and at its opposite end with a central cut-away portion 3, for purposes that will appear presently. It will be understood that the record from the hectograph carbon sheet is made in a typewriting machine on the sheet 1, and the latter is used for reproducing either by the gelatin pad method or on a rotary style duplicating machine, and the record can be made on the sheet 1 for use with

either of these types of apparatus, although the present structure is intended more particularly for use with the rotary spirit type of duplicator.

It is necessary to maintain the copy sheet 1 in operative relationship to the carbon coated sheet during the typewriting operation, and to permit quick and easy separation of the sheets afterwards without likelihood of contact between the operator's fingers and the carbon coating. To accomplish this, the copy sheet 1 is positioned against the carbon coating or hectograph ink coating 4 of the carbon sheet 5 which may be formed of any suitable weight paper, preferably of somewhat lighter weight than that of the copy sheet 1.

The carbon sheet 5 is scored or folded at one end at 6, affording the integral flange 7 which is adapted to be bent back on the body of the carbon sheet and to overlie the copy sheet 1 as shown in Fig. 1. At its opposite edge, the carbon coated sheet is scored or folded at 8 and cut away at the center at 9 to afford tabs or flanges 10 on opposite sides of the center, adapted to be bent back over the body of the carbon sheet and to overlie the copy sheet 1, as also illustrated in Fig. 1. The carbon coating 4 on the sheet 5 preferably extends to the lines 11 and 12, affording narrow uncoated surfaces between the ends of the coating 4 and the folds or creases 6 and 8, while the flange 7 and tabs 10 are also uncoated with carbon material.

The carbon coated and copy sheets are independent of each other and readily assembled, although normally held in operative relationship as shown in Fig. 1, with the copy sheet overlying the hectograph coating 4, and protecting the operator's fingers from contact therewith. After a record is made on the copy sheet 1, the latter is removed by the operator gripping the flange 7 on one side and the outer surface of the carbon sheet on the other side, holding the carbon sheet in this fashion, and gripping the finger portion or extension 2 of the copy sheet at the other end. Then by exerting a slight pulling action on the finger portion 2, the tabs 10 are forced outwardly and the copy sheet thus easily removed. This operation is facilitated by the cut-away portion 3 of the copy sheet, permitting the gripping of the flange 7 and the body of the carbon coated sheet at the central point of the flange 7 without exerting any tension or holding action on the copy sheet.

It will be understood that a suitable record may be made on the copy sheet for either the spirit or rotary style of reproducer, or for the gelatin pad type of machine. For the first mentioned use, the sheets are inserted in a typewriter so that the writing takes place on the outer surface of the copy sheet 1 as in Fig. 4, and the carbon record then appears in reverse on the opposite surface of the copy sheet 1, resulting from the adjacent carbon coated surface 4.

In order to make a record for a gelatin pad type of machine, a supplemental sheet of paper is preferably placed against the outer surface of the carbon coated sheet and the three sheets inserted into a typewriter so that the writing takes place on the outer surface of said supplemental or third sheet. The type pressing through the supplemental or third sheet and through the carbon coated sheet impress the carbon coating on to the undersurface of the copy sheet 1 where the typewritten record appears in positive, ready to be transferred to the gelatin pad.

If desirable, the carbon coated sheet can be

used more than once by inserting fresh copy sheets, until the coating material is sufficiently exhausted from the coated sheet so that it no longer functions satisfactorily. A copy sheet is inserted by slipping the end carrying the recess 3 underneath the flange 7, between it and the coated surface 4, and then bending the sheet 1 sufficiently to bring its opposite end under the tabs or flanges 10, when they are positioned as shown in Fig. 1, the sheets being then ready for insertion into a typewriter.

Where the carbon coated sheet is used several times for making successive records on a multiplicity of copy sheets, it is desirable to use every portion of the carbon coating so far as possible in order to effect uniform wear on the latter, and this is effected by positioning the carbon sheet in the typewriter in such manner that the lines of typewriting during one typing operation extend over portions of the coated surface which constitute spaces between the lines of typewriting during a succeeding operation.

This can be brought about in a variety of ways, and according to one practical adaptation of the invention, there is applied to the flange 1 a series of spaced lines indicated at 13, at the ends of the flange 1, and suitably designated by 1, 3, 5, 7, etc. 14 designate a similar set of lines at the center of the flange which are arranged parallel to the lines 1, 3, 5 and 7, and approximately in line with the centers of the spaces between said lines 1, 3, 5 and 7, the central lines being designated as 2, 4, 6, 8, etc. When using a carbon coated sheet for the first time, it is arranged in the typewriting machine so that the line of typewriting corresponds with one of the lines 1, at the ends of the flange 1, and when using the carbon coated sheet for the second time, it is positioned in the typewriting machine so that the line of writing coincides with the line 2. Continuing, when the carbon sheet is used for the third time, the line of typewriting is set to one of the lines at the ends numbered 3, and so on. In this manner, certain parallel zones of the carbon coated material are used during one typewriting operation, and during a succeeding typewriting operation, the alternate spaces between said parallel zones become the typewriting zones and receive the impressions of the type, so that the entire area of the carbon coated surface is used equally and uniformly, thus increasing the efficiency and life of the carbon coated sheet.

It will be understood that the principal feature of the invention resides in the provision of independent and separable carbon coated and copy sheets removably held together by means such as folded over flanges, tabs, or other suitable instrumentalities on one sheet engaging and overlying the other sheet and holding it against accidental displacement, while permitting ready separation of the sheets by pulling them in opposite directions against the holding action of the flanges or tabs, which together with the copy sheet, protect the operator's fingers against smudging or soiling by the ink of the coating material, and while the invention has been described with reference to a particular embodiment, it is not restricted to the exact construction or arrangement shown, and this application is intended to cover any modifications or departures coming within the purposes of the invention or the scope of the following claims.

I claim:

1. The combination with a sheet for use in making hectograph reproductions having a car-

bon coating on one side, of a copy sheet separate from the carbon sheet and positioned against said coated surface, and means carried by one of said sheets engaging the outer surface of the other of 5 said sheets and acting to hold them removably in operative relationship.

2. The combination with a sheet for use in making hectograph reproductions having a carbon coating on one side, of a copy sheet separate 10 from the carbon sheet and positioned against said coated surface, and portions carried by one of said sheets at opposite edges thereof bent back upon the body of the sheet to overlie the outer surface of the other of said sheets and acting to hold them 15 removably in operative relationship.

3. The combination with a sheet for use in making hectograph reproductions having a carbon coating on one side, of a copy sheet separate from the carbon sheet and positioned against said 20 coated surface, a flange extending along one edge of one of said sheets and tabs arranged at the ends of the opposite edge of said sheet, said flange and tabs being bent back on the body portion of the sheet to overlie the outer surface of 25 the other of said sheets and acting to hold them removably in operative relationship, the last mentioned sheet having a finger portion extending beyond the carbon coated sheet between said tabs

enabling its removal from the carbon coated sheet, and a central cut-away portion at its opposite edge.

4. The combination with a sheet for use in making hectograph reproductions having a carbon coating on one side, of a copy sheet separate from the carbon sheet and positioned against said coated surface, integral portions extending along opposite edges of said carbon coated sheet and overlying the outer surface of the copy sheet, 10 and means carried by the last mentioned sheet extending beyond the carbon coated sheet and enabling the sheets to be separated.

5. The combination with a sheet for use in making hectograph reproductions having a carbon coating on one side, of a copy sheet separate from the carbon sheet and positioned against said coated surface, an integral flange extending along one edge of said carbon coated sheet and integral tabs arranged at the ends of the opposite edge 20 of said sheet, said flange and tabs overlying the outer surface of the copy sheet and holding the sheets in operative relation and the last mentioned sheet having a finger portion extending between said tabs enabling the sheets to be separated.

RICHARD V. BOWMAN.
